UNITED STATES PATENT OFFICE.

JOHN A. AVERY, OF LAVA HOT SPRINGS, IDAHO.

LIFTING DEVICE.

Application filed May 15, 1922. Serial No. 560,997.

To all whom it may concern:

Be it known that I, JOHN A. AVERY, a citizen of the United States, residing at Lava Hot Springs, in the county of Bannock and State of Idaho, have invented certain new and useful Improvements in Lifting Devices, of which the following is a specification.

This invention relates to lifting devices, and more particularly to means for lifting motor vehicles.

An object of the present invention is the provision of means for turning a vehicle on its side to obtain ready access to the under side of the vehicle.

It is usually necessary to get under the body of a motor vehicle to make repairs, which necessitates a repairman lying on his back and working on a car or vehicle above him. In the present invention, I provide an apparatus by means of which a vehicle may be readily turned on its side which permits the repairman to work upon the under side of the car and readily obtain access to any part of it.

The device consists of a supporting member to which the vehicle is secured and means for swinging the supporting member to a substantially vertical position.

In the accompanying drawings, I have shown one embodiment of the invention. In this showing:

Figure 1 is a side elevation,

Figure 2 is a rear elevation,

Figure 3 is a detail view of a clamping member,

Figure 4 is a front elevation,

Figure 5 is a detail view of another clamping member, and,

Figure 6 is a plan view.

Referring to the drawings, the reference numeral 1 designates a pair of horizontally disposed base members adapted to be mounted on a suitable foundation, such as the floor of a garage or other flooring. These members are connected at the rear by a transverse beam 2, and are connected intermediate their ends by a flooring 3. A pair of vertical posts 4 extend upwardly from the flooring and are connected at the top by a transverse beam 5. These posts may be provided with suitable braces 6, extending outwardly at an angle (see Figure 6) and secured to the base members 1. A transverse supporting member 7 is arranged adjacent the junction of the longitudinal members and the braces.

The upper end of each of the vertical beams is formed of a pair of spaced members 8 which may be in the form of steel plates, provided with flanges 9 which are secured to the cross member 5. This provides a space for the reception of pulleys 10, mounted on pins or shafts 11.

A pair of hinged members 12 are secured to the front of the flooring 3 by means of hinges 13. These members are connected by cross members 14 spaced from each other a distance equal to the distance between the wheels of a motor vehicle. These cross members are channel shaped, forming grooves 15 for the reception of the wheels of a motor vehicle. As shown, (see Figure 6), a motor vehicle 16 is adapted to be driven on to the cross members 14 with the wheels 17 arranged in the grooves 15. The vehicle is retained in position by means of suitable clamping elements. The side of the vehicle adjacent the vertical beams is secured in position by means of substantially L-shaped clamps 18, having a horizontal portion 19, adapted to extend beneath the cross member and an up-turned end 20 adapted to be arranged on the opposite side of the cross member from the body portion. The upper end of the clamping element is provided with a hook 21 adapted to be arranged over the axle 22 of the vehicle. The clamping element is formed in two sections, having oppositely threaded ends which are connected to each other by a turn-buckle 22' to permit tightening. The other side of the vehicle is secured by means of a clamp shown in Figure 5 of the drawings. This clamp comprises a pair of complementary sections 23, adapted to be secured around the axle. A rod 24 is carried by one of the clamping sections and this rod is provided with an angular portion 25. A second rod 26 is swiveled on each of the hinged members 12 and these two rods are provided with oppositely threaded ends adapted to be connected by a turn buckle 27.

The outer ends of the hinged members 12 are provided with side plates 28, extending beyond the hinged members and connected to each other by blocks 29. Pulleys 30 are arranged between these plates, the pulleys being mounted on shafts 31.

A rope 32 is secured in an eye-bolt 33, carried at the upper end of each of the vertical members 4. These ropes extend over pulleys 30 and thence over pulleys 10,

the pulleys being provided with suitable grooves for the reception of the ropes. The ropes are then carried downwardly adjacent the vertical members and pass over pulleys 34, mounted in suitable supports on the flooring 3. Thence, they pass over guide pulleys 35. The ends of the ropes are secured to a drum 36, rotatably mounted in the vertical members 4. One end of the drum is provided with a shaft extending through the vertical member and carrying a gear 37. A pinion 38 is mounted on a stub shaft on the outside of the supporting member and meshes with the gear 37. This pinion is provided with an operating crank 39 and a suitable locking member 40, may be arranged adjacent the crank. A coil spring 41 may be arranged on the flooring adapted to contact with the rear cross member 14 when the parts are in raised position.

The operation of the device will be apparent from the foregoing description. The vehicle is first run on to the cross members with the wheels 17 received in the grooves 15. It is then clamped in position to prevent displacement and raised to the dotted line position shown in Figure 1 of the drawings by winding the ropes 32 on the drum 36. By means of the gearing shown, the vehicle can be raised with ease by one man. When the vehicle is in raised position, the locking member 40 is arranged over the crank to prevent accidental lowering. The spring 41 engaging a portion of the movable support, tends to take up any lost motion and retain the parts rigid.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. A lifting device for motor vehicles comprising a base, a pair of spaced vertical members secured to said base, a pair of supporting members hinged to said base adjacent said vertical members, means for supporting a vehicle on said supporting members, and means connected between the free ends of said supporting members and the

upper ends of said vertical members for raising the free ends of said supporting members, said raising means being arranged to permit a vehicle to enter therebeneath parallel to said vertical members.

2. A lifting device for motor vehicles comprising a base, a pair of spaced vertical members secured to said base, a pair of supporting members hinged to said base adjacent said vertical members, a pair of cross beams secured to said supporting members, said cross beams being spaced from each other a distance equal to the wheel gage of a motor vehicle and being provided with grooves for the reception of the vehicle wheels, means for clamping the vehicle to said beams, and means connected between the free ends of said supporting members and the upper ends of said vertical members for raising the free ends of said supporting members, said raising means being arranged to permit a vehicle to enter therebeneath parallel to said vertical members.

3. A lifting device for motor vehicles comprising a base, a pair of spaced vertical members secured to said base, a pair of supporting members hinged to the base adjacent said vertical members, means for supporting a vehicle on said supporting members, ropes secured to the upper ends of said vertical members, pulleys arranged adjacent the free ends of said supporting members, said ropes being passed around said pulleys and then extended toward the top of said supporting members, said vertical members being provided with openings for the reception of pulleys near their upper ends, pulleys arranged in said openings, said ropes being passed over said last named pulleys, and a drum mounted on said base, the ends of said ropes between the free ends of said supporting members and the upper ends of said vertical members being spaced therefrom a sufficient distance to permit a vehicle to pass thereunder along said vehicle supporting means parallel to said vertical members.

In testimony whereof I affix my signature in presence of two witnesses.

JOHN A. AVERY.

Witnesses:

B. W. KEMPER,
RUTH M. CHANDLER.
